LUTHER L. KNOX, OF BELLEVUE, PENNSYLVANIA, ASSIGNEE TO KNOX PRODUCTS COMPANY, OF PITTSBURGH, PENNSYLVANIA, A CORPORATION OF PENNSYLVANIA

METHOD AND APPARATUS FOR REFRIGERATING

Application filed September 22, 1926. Serial No. 136,983.

This invention relates to a method and apparatus for refrigerating, and is particularly useful in connection with "mechanical refrigeration" systems wherein a refrigerating medium, such as ammonia or methyl chloride, is alternately compressed and expanded.

Such systems as heretofore employed are open to numerous disadvantages. The expansion coil is located either directly in the food-containing compartment or else is so connected thereto that free air circulation obtains. The coil is maintained at a temperature considerably below that found in refrigerators using ice, and it is found that as a result the foods in the compartment are rapidly dehydrated. The moisture leaves the food, and as the air circulates in the compartment it freezes on the outside of the expansion coil and materially reduces its efficiency, in addition to reducing the quality of the food in the compartment. This reduction in efficiency is so great that it is necessary to put the unit out of operation at regular intervals for a long enough period to permit "de-icing", that is to say, to permit of the collected ice melting off the coil.

I provide for supplying a refrigerating medium, as for example, ammonia or methyl chloride, to a heat transfer unit, circulating a liquid between the place or compartment to be refrigerated and the heat transfer unit, and maintaining the liquid at such temperature that the compartment or the compartment walls are maintained above the freezing point.

With this arrangement the food is not dehydrated, and since there is no opportunity for frost forming on the expansion coils, de-icing is obviated and the unit may be operated continuously.

Preferably, my invention will be embodied in an insulated cabinet having a compartment therein, this compartment being double-walled to permit of circulating the liquid. The space between the double walls and above the compartment comprises a container for the liquid, and the heat transfer unit will preferably be placed in the top of this container. It will be seen that ordinary water might be used, since it is intended to maintain

the liquid above the freezing point, but I preferably employ a solution of a salt such as calcium chloride. The calcium chloride may be placed in a permeable holder in the container so that the unit may be shipped "dry" and may then be charged with ordinary water. By this arrangement the solution is maintained saturated and the deposition of salt in the lower parts of the liquid container is eliminated.

It is customary in mechanical refrigeration systems to provide for the freezing of water in small pans so as to provide ice cubes for consumption. I provide a special compartment cooled by the heat transfer unit proper, while the main compartment is cooled through the liquid medium.

Certain foods, notably butter, will acquire the odor of other foods in the refrigerator, and I therefore provide a plurality of compartments which are substantially isolated from one another. The several compartments may be portions of a single large compartment, and preferably a single door is employed. Yieldable packing means are employed for cooperating with the partitions between the compartments for closing them off from one another. This has been found in actual practice to prevent air circulation through the refrigerator and consequent acquisition of food odors by other substances in the same refrigerator. In order to make a more sanitary refrigerator I may employ removable liners for the several portions of the compartment.

In the accompanying drawings, which illustrate a preferred form of the invention as applied to a household refrigerator—

Figure 1 is a vertical section through a refrigerator taken on the line I—I of Figure 2;

Figure 2 is a vertical section taken on the line II—II of Figure 1;

Figure 3 is a horizontal section taken on the line III—III of Figure 1;

Figure 4 is a perspective view, partly in section, showing the food compartment and the liquid container; and

Figure 5 is a vertical section through a modified form of food compartment showing

the use of liners for the several compartment partitions.

In the illustrated embodiment of the invention there is shown a refrigerator comprising an outer shell 2, in the lower portion 3 of which there is placed a compressor and associated mechanism for handling a refrigerating medium such as ammonia or methyl chloride. The upper portion of the shell 2 forms the refrigerator proper, and it has a food compartment indicated generally by the reference character 4. This food compartment is shown in more detail in Figure 4. It comprises a bottom 5, a back wall 6, side walls 7 and a top wall 8. Extending upwardly from the top 8 is a box-like container, indicated generally by the reference character 9. The container 9 is larger than the compartment 4, thus forming, in effect, a double-walled structure adapted to receive a liquid 10.

As best shown in Figure 2, the container 9 is substantially filled with liquid, preferably a calcium chloride solution. The container extends almost to the top of the refrigerator and is provided with a top 11. An insulating cover 12 forms the top of the unit.

A heat transfer unit, indicated generally by the reference character 13, is mounted in the upper portion of the container 9. This unit is connected to the compressor and associated apparatus mounted in the compartment 3, so that the refrigerating medium is circulated through the heat transfer unit 13. The particular form of compressor mechanism forms no part of the present invention. I have therefore only indicated portions thereof by dotted lines in Figure 2. There is shown a motor 14 connected to a compressor 15 and provided with a speed-regulating rheostat 16 whereby the operation of the apparatus may be varied as desired.

In operation, the liquid 10 circulates in the space between the walls of the food compartment 4 and the container 9, thus maintaining the food compartment at reduced temperature. The temperature maintained in the food compartment may be varied by adjusting the rheostat 16.

As above stated, it is preferred to use a calcium chloride solution in the container 9, and I therefore provide a permeable holder, such as a fabric bag 17, in the container 9. This bag is filled with a mixture of calcium chloride and lime, so that the unit may be shipped dry and merely filled with water to put it in condition for operation. The use of the bag insures that a proper solution will be maintained and that no salt will accumulate in the bottom of the container.

The food compartment 4 is, of course, provided with a door 18, as shown. The compartment is provided with shelves which may be the wire gratings ordinarily employed, but which are preferably metal partitions 19 which divide the compartment 4

into isolated partitions. Yieldable packing members 20 are provided on the door 18. These packing members cooperate with the edges of the partitions 19 to substantially seal off the compartment portions one from the other and thus prevent air circulation within the refrigerator. This is found to be of great value in eliminating the acquiring of certain food odors by other foods in the refrigerating compartment 4. Further packings 21 are provided on the outer portions of the door 18 for sealing off the food compartment from the exterior.

It may be desirable to maintain the different individual compartment portions at different temperatures, and this may be accomplished by shaping the liquid container 9 as shown in Figures 2 and 4. Instead of the container being of uniform width from top to bottom, the side portions thereof are tapered so that at the bottom of the food compartment 4 a smaller area for heat transfer between the food compartment and the cooling medium is afforded than in the upper portions of the food compartment. In this manner the various compartment portions, or individual compartments as they may be termed, may be maintained at different relative temperatures.

In order to form ice cubes, the heat transfer unit 13 is provided with a supplemental coil 22 within which drawers 23 may be placed. These drawers are of the usual form, having pockets which may be filled with water to be frozen into cubes of ice. The coils 22 are not immersed in the solution 10, as a partition 24 is provided for isolating them from the container 9. The partition 24 forms a compartment 25, and it will be noted from Figure 2 that the door 18 is effective for closing off this compartment, as well as the main food compartment 4.

For sanitary reasons it is desirable to have a glass-like finish on the interior of the food compartment, and in Figure 5 I show a way in which this object may be inexpensively attained. In this form of the invention parts corresponding to similar parts already described are given the same reference character with an "a" suffixed thereto. Each of the compartment portions into which the food compartment 4^a is divided by partitions 19^a is supplied with a metal liner 26. This may be formed from enameled metal and put into place. Each liner has flanges 27 and the flanges of adjacent liners overlap, as shown in Figure 5. The packings 20 bear against these flanges 27 and thus isolate the compartment portions from one another. The liners may be held in place in any desired manner, and if they become chipped they are readily replaceable.

I have illustrated and described a preferred embodiment of the invention, but it will be understood that it is not limited to the

form shown since it may be otherwise embodied and practiced within the scope of the following claims.

I claim:—

5. 1. A refrigerator comprising a plurality of open sided compartments, a door for closing the open sides of the compartments, and packing strips cooperating with the door and the edges of the compartments for substantially isolating the compartments from one another. 70
10. 2. A refrigerator comprising an open sided compartment divided into portions by partitions, a door for closing the open side of the compartment, packing strips cooperating with the door and the partitions for substantially isolating the compartment portions from one another, and liners for the individual compartment portions. 75
15. 3. A refrigerator comprising a compartment, a partition dividing the compartment into isolated portions and means for supplying a cooling medium to the walls of the compartment, the last mentioned means having a gradually varying dimension whereby it is effective for cooling different compartments in different amounts. 80
20. 4. A refrigerator comprising a compartment, and means for supplying a cooling medium to the walls thereof, the portions of the walls which are exposed to the cooling medium decreasing in area from top to bottom of the compartment. 85
25. 5. A refrigerator comprising an insulated compartment, non-insulating partitions dividing the compartment into substantially isolated portions, and removable liners for the individual portions. 90
30. 6. A refrigerator comprising a compartment, a jacket therefor extending above the compartment and adapted to hold a liquid, a heat transfer unit in the jacket above the compartment, and a freezing compartment adapted for direct cooling by the heat transfer unit. 95
35. 7. A refrigerator comprising a compartment, a jacket therefor extending above the compartment and adapted to hold a liquid, a heat transfer unit in the jacket above the compartment, a freezing compartment adapted for direct cooling by the heat transfer unit, and a common door for closing the first mentioned compartment and the freezing compartment. 100
40. 8. A refrigerator comprising a compartment, a jacket for the walls thereof, said jacket decreasing in width in the general direction of the compartment walls from top to bottom thereof and means for supplying a cooling fluid to the jacket. 105
45. 9. A refrigerator comprising a heat transfer unit, a plurality of compartments, at least one of said compartments being cooled directly by the heat transfer unit, and means for circulating a liquid between the heat 110
50. 115
55. 120
60. 125

transfer unit and another of said compartments.

10. The method of refrigeration which comprises supplying a refrigerating medium to a heat transfer unit, circulating a liquid between the place to be refrigerated and the heat transfer unit, and varying the area of the place to be refrigerated exposed to the liquid in accordance with the distance from the heat transfer unit.

In testimony whereof I have hereunto set my hand.

LUTHER L. KNOX.
